WINFIELD S. WARDELL, OF NEWARK, NEW JERSEY, ASSIGNOR TO SARAH A. E. WARDELL, OF NEWARK, NEW JERSEY.

VALVE.

1,261,078.

Specification of Letters Patent. Patented Apr. 2, 1918.

Application filed May 7, 1914. Serial No. 836,854.

To all whom it may concern:

Be it known that I, WINFIELD S. WARDELL, a citizen of the United States, and a resident of Newark, in the county of Essex and State of New Jersey, have invented certain Improvements in Valves, of which the following is a specification.

This invention relates more particularly to that class of valves adapted to close automatically, and was designed especially as a ball-cock valve for use in connection with the water supply of a flushing tank. It is to be understood, however, that I do not restrict myself to any particular use of my invention by disclosing the same in connection with a flushing tank, such disclosure being for illustrative purposes only.

The objects of the invention are to provide an improved valve which will automatically close with the pressure of the water; to provide novel and effective means for opening said valve; to reduce the pressure of water as it passes through the valve and prevent the flow of water from being heard; to cushion the flow of water and spread the discharged water into a film; to secure simplicity of construction and operation, and to obtain other advantages and results as may be brought out in the following description.

Referring to the accompanying drawings, in which like numerals of reference indicate the same parts throughout the several views,

Figure 1 is a vertical sectional view of a tank showing a valve embodying my invention mounted therein;

Fig. 2 is a vertical longitudinal section through said valve of Fig. 1 upon an enlarged scale, and

Fig. 3 is a similar sectional view showing a modified construction of valve.

In the specific embodiment of the invention illustrated more especially in Figs. 1 and 2 of the drawings, the reference numeral 1 indicates a tank in the bottom 2 of which my improved valve is shown mounted. Said valve provides at its bottom an attaching member or coupling 3, preferably cylindrical, having a peripheral flange 4 at its top and being screw-threaded from its bottom upward to receive a nut 5. An appropriate hole 56 is made in the bottom 2 of the tank and the coupling 3 inserted in the same with the flange 4 upon the inside and the threaded portion protruding upon the out-

side. The nut 5 is then applied to clamp the flange 4 to the bottom 2 of the tank. Furthermore, said coupling is hollow, providing therein a valve chamber 6, and screwed into the top of this chamber is a 60 nipple 7 the lower end of which depends within the chamber 6 providing at its lower extremity a downwardly facing valve seat 8. At its upper end this nipple 7 is exteriorly screw-threaded and receives an upwardly extending shell or tubular discharge nozzle 9.

A movable cap 10 overlies the open upper end of the nozzle 9 and depending from said cap centrally within the nozzle is a rod 11, 70 said rod extending also through a central longitudinal aperture 12 in the nipple 7. As shown, this aperture 12 extends upwardly through the valve seat 8 and for its lower portion provides a restricted passage 75 13 of only slightly greater diameter than the diameter of the rod, said aperture 12 widening at its upper portion and providing an enlarged passage 14. Obviously, therefore, water may flow upwardly through 80 the valve seat around the rod 11 within the restricted passage 13 into the enlarged passage 14.

In order to stop the flow, I provide a ball or other valve 15 adapted to seat upwardly 85 against said valve seat 8 of the nipple 7 and close the passage 13 therethrough. This ball may be of any suitable material, but is preferably light and sufficiently elastic to effect a tight closure against the seat. I 90 have found rubber answers these requirements very well, but I do not restrict myself to the use of this or any other specific material. The flow of water upward toward the passage 13 normally carries the 95 ball 15 against its seat 8 with considerable energy, and the rod 11 which normally protrudes a distance through said seat will be pushed upward by said ball at the proper time and the cap 10 raised.

In order to prevent the water from leaving the tank when the pressure in the supply pipe decreases, I provide a bottom 16 to the chamber 6 containing the ball or valve 15, and through said bottom provide a hole 17 105 for admitting the water but too small to allow the ball to pass downward into the supply pipe. When the pressure above the ball becomes greater than the pressure of supply, the ball will drop down to the bottom 16 and 110

lodge in the hole 17, thereby preventing any back flow of the water.

Depending peripherally downward from the cap 10 is a sleeve 18 which surrounds the shell or nozzle 9 and terminates adjacent its bottom, said sleeve being shown as integral with said cap. Furthermore, the sleeve is enough larger than the shell to provide a narrow annular discharge passage 19 therebetween, which opens downwardly. It will be noted that the sleeve 18 terminates near the bottom of the tank, and as there is always a little water left in a flushing tank, I have arranged that the lower end of the sleeve remain immersed at all times. The water issuing from the discharge passage 19 will be film-like and will intermingle with the water in the tank without the usual noisy disturbances accompanying this operation in other devices.

In order to admit the water from the interior of the shell 9 to the discharge passage 19, I provide a circumferential series of apertures 20 in said shell preferably near its top. As the pressure of water becomes too great within the shell, the cap 10 will be lifted, which operates to allow the ball to approach its seat and partially or entirely shut off the flow, thus reducing the pressure within the shell. Obviously, substantially even pressure of water as it discharges into the tank will be maintained. I also provide in the shell or nozzle 9 a plurality of holes 21 adapted to admit small streams of water into the discharge passage 19 near the lower end of the sleeve, said streams being directed transversely against said sleeve at various circumferential points so as to balance the same and prevent chattering thereof.

Extending upwardly at the side of the shell or nozzle 9 is a post 22 shown in the drawings as secured to the flange and terminating at its top opposite the cap 10. Pivoted to the upper end of this post and arranged to swing downwardly into a slot 100 in the top 101 of said cap 10 is a transverse lever 23 providing an arm 24 to which a balancing weight 25 is affixed. Said weight is shown herein as a small ball screwed upon a carrier 26 which may be clamped by a set screw 27 at any desired position along the arm 24. Preferably the end of the arm 24 is threaded to also receive the ball, if desired.

In operation, the weight 25 is arranged upon the lever arm 24 at such a point that its moment in air will be sufficient to maintain the cap 10 and ball or valve 15 depressed against the pressure and flow of water, but, when immersed, said weight has not a sufficient moment to withstand the lifting effort of the ball or valve 15, so that the valve will close against its valve seat and stop further flow of the water.

Although I much prefer to close the valve 15 as above described with the pressure, I can

also adapt my valve to close against the pressure, as shown in Fig. 3 of the drawings. Here, as in the preferred construction, my valve provides a hollow coupling 28 at its bottom into which screws a nipple 29 having at its lower end a central restricted passage 30 which widens at the upper end of the nipple into an enlarged passage 31. Through these passages 30 and 31 extends a rod 32 as before, which depends from a cap 33 at the upper end of a nozzle 34 upon the nipple, said cap having a sleeve 35 loosely surrounding said nozzle.

Within the enlarged passage 31 and upon the rod 32 is a washer 36 of less diameter than said passage and prevented from moving upward on the rod by any suitable means, such as a transverse pin 37 in the rod just above the washer. With the rod and cap in their lowered positions, this washer is arranged to fit downwardly over the restricted passage 30 and prevent the water from flowing into the enlarged passage. For holding the cap down when the tank is full, I pivot a lever 38 intermediate of its ends, as at 39, to a post 40 at the side of the cap, one end of said lever having a slot and pin connection with the cap and the other end being equipped with the usual ball float (not shown) common in the art.

In my improved construction a refill tube 55 is preferably mounted on the top of the cap, as shown in Fig. 1, communicating with the interior of the cap and therefore with the flow of water through the nozzle. This refill tube 55 is thus removable with the cap, and can be taken out for examination or repairs with great ease and facility.

Obviously detail modifications may be made in manufacturing my improved valve without departing from the spirit and scope of the invention, and I do not wish to be understood as limiting myself except as required by the following claims when construed in the light of the prior art.

Having thus described the invention, what I claim is:

1. In a valve, the combination of a nozzle, means for admitting a flow of water to said nozzle and for stopping said flow, a cap for the outlet end of said nozzle, a sleeve depending from said cap around the nozzle in substantially parallel relation thereto and providing between itself and the nozzle a discharge passage of constant cross-sectional area, said nozzle having a plurality of small holes in its side arranged in a circumferential series through which water may flow to engage and hold said sleeve away from the sides of the nozzle.

2. In a valve, the combination of a nozzle, means for admitting a flow of water to said nozzle and for stopping said flow, a cap for the outlet end of said nozzle, a sleeve depending from said cap around the nozzle

in substantially parallel relation thereto and providing between itself and the nozzle a discharge passage of constant cross-sectional area, said nozzle having a plurality of small holes in its side near its inlet end arranged in a circumferential series through which water may flow to engage and hold the free end of said sleeve away from the sides of the nozzle so as to prevent the same from 10 chattering.

3. In a valve, the combination of a nozzle, valve means for admitting a flow of water to said nozzle and for stopping said flow, a cap movable toward and away from the 15 outlet end of said nozzle, a rod carried by said cap and extending through the nozzle

for operating said valve means, a sleeve depending from said cap around the nozzle and providing between itself and the nozzle a discharge passage of constant cross-sectional area for its entire length said nozzle having a plurality of circumferential series of holes in its sides the holes of the series near the inlet end of the nozzle being small 20 in diameter, said holes being adapted to direct the water in jets against the said sleeve for holding said sleeve away from the sides of the nozzle so as to prevent chattering. 25

WINFIELD S. WARDELL.
